UNITED STATES PATENT OFFICE.

HARRY McCORKEL, OF LAPORTE, INDIANA.

APPLIANCE FOR FOUNDRY MOLDS.

1,405,929.

Specification of Letters Patent. Patented Feb. 7, 1922.

Application filed May 9, 1919. Serial No. 295,892.

To all whom it may concern:

Be it known that I, HARRY McCORKEL, a citizen of the United States, and a resident of the city of Laporte, county of La-
5 porte, and State of Indiana, have invented certain new and useful Improvements in Appliances for Foundry Molds, of which the following is a specification.

My invention relates to an appliance for 10 foundry molds, and has for its object the provision of a device which will facilitate the handling and operation of a foundry mold. A further object is the provision of a device which will afford a means of pivotally connecting the various parts of a foundry mold. Another object is the provision of a device which will afford a means of pivotally loosely mounting a pattern upon a drag of a mold.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1, is a perspective view of a mold embodying the invention,

30 Fig. 2, is a sectional view of one of the devices applied, with parts removed,

Fig. 3, is a perspective view of a mold embodying the invention, showing the cope and pattern plate rolled back,

35 Fig. 4, a front elevation of the pattern plate embodying part of the invention,

Fig. 5, a top plan view of one part of the invention, and

Fig. 6, a top plan view of a co-operating 40 part of the invention.

In foundry molds, it has been difficult to provide a means of pivotally connecting the cope of the mold with the drag of the mold, inasmuch as the pattern plate is adapted to 45 be engaged between these two parts. By my invention I have provided a means whereby the cope and the drag of the mold may be swingingly loosely connected to an additional means, whereby the pattern plate 50 is adapted to swing vertically relatively to the drag of the mold.

The cope 8 of the mold has secured to one

side the trunnion-bearing member 9, having a base 10, which has a flange-like member 11 extending at right angles thereto. One end 55 of the member 9 has projecting, from opposite sides thereof, trunnions 12, the portion of the member 9 from which said trunnions project being rounded to form a cylindrical portion 12'. The members 10 and 11 have 60 openings 13 projecting therethrough, through which suitable fastening means are adapted to pass in order to secure the member 9 to the cope 8. Securely fastened to the drag 7 of the mold by suitable fastening means which project through the openings 13', is a member 14, having at its base a flange-like member 16, said flange-like member 16 having projecting at right angles thereto and made integral therewith a 70 flange-like member 15. The member 14 is adapted to co-operate with the member 9 and consequently is formed bifurcate, so as to provide the elements 14' which are spaced from each other, said elements 14' forming 75 the cheeks of a trunnion plate at the outer ends of which are formed grooves or sockets 17 adapted to receive and engage the trunnions 12, the portion 12' being engaged between the outer ends of the members 14'. 80 Adjacent the end of the member 14' at which the member 16 appears, is a secondary socket or groove 22. Provided in the member 9 is a socket or groove 23, which is adapted to register with the socket or groove 85 22 when the member 11 is in engagement with the member 15 and the trunnions 12 engaged in the sockets 17. The pattern plate 18 is formed with a flange 19 projecting laterally therefrom, said flange 19 90 being slotted adjacent one end, thereby forming the spaces 20 therein. Securely fastened to the flange 19 and traversing the slotted portion 20 are cylindrical pins 21, said pins 21 being adapted, when said pattern 18 is in operative position within the drag 7, to rest in and be engaged by the sockets 22 formed in the members 14'.

By this arrangement it is evident, as shown in Fig. 3, that the pattern will be 100 pivotally mounted upon the pins 21 when said pins 21 are engaged by the slots 22, thereby affording a means of swinging the pattern plate on said pins 21 as an axis rela-

tively to the drag 7. It is also evident that the cope is pivotally mounted on the drag 7 when the trunnions 12 are resting in and engaged by the socket or groove 17. When 5 the cope, drag and pattern are assembled in operative position, as shown in Fig. 1, it is evident that the pattern plate is mounted upon the pins 21 as an axis, said pins resting in the socket or groove 22 which is formed 10 in members 14'. It is also apparent that the cope is mounted upon the pins 21 as an axis, said pins 21 being engaged by the sockets or grooves 23 which are formed in the members 9. Consequently, upon raising the forward 15 end of the cope 8, the said cope will swing upon the pins 21 as an axis, inasmuch as the trunnions 12 are raised clear of the base of the sockets 17 while the cope is in this position. Upon raising the cope upwardly at 20 its forward end, the trunnions 12 are moved downwardly into engagement with the member 14 at the base of the sockets 17. As soon as the trunnions come into contact with the members 14 in this manner, any further 25 raising of the forward end of the cope 8 will cause the cope to swing upon the trunnions 12 as an axis. When the device is in operative position, as shown in Fig. 1, the 30 cope and the pattern plate may both be swung upwardly at the same time, and in this case the cope and pattern plate would swing upwardly on the pins 21 as an axis until the trunnions 12 came into contact with the members 14. Further upward swinging 35 of the forward ends of these members would then cause the cope 8 to swing upon the trunnions 12 as an axis and would cause the pattern plate to continue to swing upon the pins 21 as an axis. Consequently, it is seen 40 that I have provided a means of mounting the cope upon the drag of the mold, whereby said cope will be mounted upon an axis and adapted for swinging movement relative to the drag when said pattern plate is not in 45 position in the drag. By my invention I have also provided means whereby the cope will be pivotally mounted upon the drag of the mold when the pattern plate is in operative position in the mold. By this means 50 I have provided a device by which the cope may be removed from the drag of the mold vertically upward in a swinging position, entirely free from any lateral movement, inasmuch as the portions 12', being snugly 55 engaged by the outer ends of the members 14', will serve to prevent lateral movement of the cope while the same is swinging upward. After forming an impress in the sand which is contained in the cope and the drag, 60 it is necessary to remove the pattern plate before pouring, and in order to do this it is necessary to remove the cope from its assembled position with the drag. In raising the cope from the drag, it frequently happens 65 that a slight lateral motion is given to the

cope, with the result that the sand is broken loose by coming into contact with the pattern or from the jar naturally incidental thereto in such a method. The necessity then arises of repairing whatever damage 70 has been done to the imprint made in the sand, with the consequent result of an expenditure of time and material. It frequently happens that the damage occasioned by such a method is such as to be irreparable, 75 and thereby the necessity of forming a new impression arises. These difficulties are eliminated by the provision of the device just described, and I have thereby greatly increased the efficiency of a foundry mold. 80

While I have illustrated and described the preferred form of construction for carrying my invention into effect, this is capable of variation and modification without departing from the spirit of the invention. I, 85 therefore, do not wish to be limited to the precise details of construction set forth, but desire to avail myself of such variations and modifications as come within the scope of the appended claims. 90

Having described my invention, what I claim as new and desire to secure by Letters Patent is:—

1. In combination with a foundry mold, a pattern plate; flanges on said plate adapted to be engaged between the cope and the drag, one of said flanges being slotted adjacent opposite ends; axes secured to said flange and traversing said slots; means co-operating with said axes, whereby the cope 95 and said plate are adapted to swing vertically on said axes; and secondary axes secured to said cope, co-operating with said means upon which said cope is adapted to swing, said cope swinging clear of said axes 100 upon said secondary axes coming into contact with said means, substantially as described.

2. In combination with a foundry mold, a pattern plate; axis secured to one side of 110 said plate; a member fastened at one end to the cope of said mold, said member having a socket adjacent said end adapted to engage said axis; trunnions projecting from opposite sides of the opposite end of said member; and a trunnion plate fastened at one end to the drag of said mold, said plate having a socket adjacent said end adapted to engage said axis, and having a socket adjacent the opposite end adapted to engage 115 said trunnions, substantially as described.

3. In a foundry mold, means secured to said mold, whereby said cope is adapted to swing upwardly from the drag, said cope being pivoted at one point during a portion of said movement, and pivoted at another point during the remainder of said movement, substantially as described. 125

4. In a mold containing a pattern plate, means for swinging the cope and said plate 130

upwardly from the drag, said cope swinging, during a portion of its movement, on the same axes with said pattern plate, and during the remainder of its movement on an axis independent of said pattern, substantially as described.

In testimony whereof I have signed my

name to this specification in the presence of two subscribing witnesses.

HARRY McCORKEL.
